UNITED STATES PATENT OFFICE.

ARTHUR WAYLAND PRESCOTT, OF BINGHAMTON, NEW YORK.

REGISTER.

1,233,125

Specification of Letters Patent. Patented July 10, 1917.

Application filed July 8, 1916. Serial No. 108,170.

To all whom it may concern:

Be it known that I, ARTHUR W. PRESCOTT, a citizen of the United States, and a resident of Binghamton, in the county of Broome and State of New York, have invented new and useful Improvements in Registers, of which the following is a specification.

My invention is an improvement in registers, and has for its object to provide a form 10 of supporting frame for the louvers and a form of face plate or grill so arranged that the connection between the grill and the supporting frame will be concealed, and wherein the operating mechanism for opening and 15 closing the louvers is mounted upon rollers for movement in a single plane, and wherein the said mechanism is connected to the louvers in such manner that the pull on the louvers will be approximately perpendicular 20 to their planes.

Figure 1 is a partial top plan view of the improved register,

Fig. 2 is a section on the line 2--2 of Fig. 1, looking in the direction of the arrows adjacent to the line,

Fig. 3 is a section on the line 3--3 of Fig. 2 looking in the direction of the arrows adjacent to the line.

Fig. 4 is a partial perspective view looking at the inside,

Fig. 5 is a partial perspective view of one of the louvers.

Fig. 6 is a perspective view showing a modified form of foot plate, and

Fig. 7 is an end view of the same.

The present embodiment of the invention is shown in the opening 1 of a floor 2 or the like, and the improvement comprises a rectangular frame consisting of side walls 3 and end walls 4, the side and end walls having lateral outwardly extending flanges 5 at their upper edges, for engaging the upper surface of the floor 2, to support the frame within the opening. One of the end walls 4 has an inwardly bent flange at its lower edge forming a trough or trackway 6, for a purpose to be later described, and the said walls 3 have inwardly extending oblique flanges 7 at their lower edges.

The end walls 4 support the louvers or valves 8 each of the said louvers having a bearing 9 at each end and at its center which is adapted to receive a stub shaft or journal pin 10 connected with the adjacent end wall 4. At that wall 4 having the trough 6, the shafts or journal pins 10 engage openings in

the side walls of the trough, and the opposite wall 4 may have a flange for a like purpose.

It will be noticed from an inspection of Fig. 5 that each louver is grooved longitudinally at its center, and that the bearings 9 are in these grooves. At opposite sides of the grooves the louvers are curved slightly as shown, to engage at their opposite side edges 65 in the manner shown in Fig. 3, to make a tight closure in the frame, when the said valves or louvers are closed.

The face plate or grill 11, which is of cast material, has the usual openings for 70 the passage of air, the said plate being of larger size than the frame and extending beyond the frame at the opposite sides thereof to lap upon the floor as shown. The outer edge of the face plate is ribbed on its 75 under surface as shown at 12, for engaging the floor, and adjacent to each side 3 of the frame, the face plate has an inwardly and downwardly extending oblique flange 13. Each of the sides 3 is provided at the flange 80 5 with an inwardly bent angular portion 14, the upper wall of the said portion being shaped to lap upon the under face of the adjacent flange 13, and screw bolts 15 are passed through openings in the flange and 85 through slots 16 in the said upper wall of the inwardly bent portion to connect the frame with the face plate.

The bolts 15 are near the ends of the sides 3, and the lower wall of the inwardly bent portion provides a lock for holding the nut from turning while the connection is being made, and access is permitted to the screw bolts through the openings of the face plate.

Each louver is provided near one end and 90 near one side edge with a bearing 17, and each of these bearings is adapted for engagement by one of the arms 18 of a crank. The other arm 19 of each crank shaft engages a slide or carriage 20 mounted to 100 move on rollers 21, running in the trough shaped guideway, the said rollers having concave or grooved peripheries for engagement by the slide or carriage.

The said slide is formed by bending the 105 side edges 22 and 23 of a plate, laterally, the lower edge 22 being of angular form, forming an angular rib for engaging the roller, while the upper edge is oblique, and the free edges of the said edges move in contact 110 with the inner face of the adjacent side wall 4. A stop 24 extends inwardly from the

said side wall 4, engaging the upper surface of the edge 23, to prevent upward movement of the slide or carriage, and to hold it in contact with the roller.

5 The carriage is moved by means of a foot plate 25, which extends upwardly through a slot 26 in the face plate 11. The said slot is provided at each end with indications, the letters O and S in the present instance, indicating that when the foot plate is adjacent to the letter "O" the louvers will be open, while when the foot plate is adjacent to the letter "S" the louvers will be closed. It will be evident that when the foot plate 24, 15 whose upper face is roughened in the usual manner, is pushed longitudinally of the register, the carriage moves upon the rollers 21 without friction, and the pull upon the louvers by the crank shafts 18-19 is nearly 20 perpendicular to the planes of the louvers so that friction is reduced to a minimum.

The arrangement of the flanges 13 and the inwardly bent portions 14 permits the connection of the face plate with the frame to be concealed, and it is not necessary to provide openings in the edge of the face plate for receiving bolts or screws to connect the face plate. If desired, the screw bolts 15 may be dispensed with and their place taken by ordinary wood screws which will engage the floor or joists. The face plate, it will be noticed, has its edges rounded and brought to a sharp edge at the floor line. The foot plate has no lateral movement with respect to the plane of the face plate, that is when the register is horizontal, the movement of the foot plate is altogether horizontal, while when the register is vertical, the movement of the foot plate will be altogether vertical. 35 The crank arms 18 are journaled in the bearings 17 to move freely therein, and the entire weight of the operating device and any pressure exerted on same, is supported by the wheels or rollers.

40 In Figs. 6 and 7 is shown a modified form of foot plate. In this construction the carriage 22^a and 23^a is similar to the carriage 22-23, and the foot plate 30 has oppositely extending lugs or branches 31 at its lower end. Inclined shoulders 32 are formed between the branches and the body of the plate at their junction, the said shoulders being at opposite sides of the foot plate. The ends of the branches are beveled to fit smoothly 50 within the edge 22^a of the carriage, and lugs 33 struck up from the edge 23^a of the carriage are bent over upon the shoulders to prevent upward movement of the plate. The foot plate is thus held to the carriage 55 without rivets, screws or the like.

I claim:

1. In a device of the character specified, a face plate or grill having an imperforate edge and provided at the inner side of the 65 said edge with inwardly and downwardly

extending oblique flanges, a louver supporting frame having the upper edges of its side and end walls provided with outwardly extending lateral flanges for engaging beneath the imperforate edge of the grill, and the 70 walls of the frame having inwardly bent angular portions abutting the under faces of the flanges, and means for connecting the flanges with the angular portions.

2. In a device of the character specified, a 75 face plate or grill having an imperforate edge and provided at the inner side of the said edge with inwardly and downwardly extending oblique flanges provided with openings for permitting the supporting 80 frame for the louvers to be connected to the grill.

3. In a device of the character specified, a louver supporting frame, louvers mounted to swing on parallel axes on the lower edge 85 of the frame, the side walls of the louver supporting frame having inwardly extending flanges for engagement by the louvers, a channel trackway at one end of the frame, rollers loosely mounted in the trackway, a 90 slide or carriage movable on the rollers, and a connection between the said slide or carriage and each louver for simultaneously swinging the louvers, said slide or carriage having a foot plate for operating the same, 95 said connection comprising cranks each having a portion journaled in the carriage and a portion journaled on the louver.

4. In a device of the character specified, a 100 louver supporting frame, louvers mounted to swing on parallel axes at the lower edge of the frame, a channel trackway at one end of the frame, rollers loose in the trackway, a slide or carriage movable on the rollers, and a connection between the said 105 slide or carriage and each louver for simultaneously swinging the louvers.

5. In a device of the character specified, the combination with a louver supporting frame and the louvers mounted to swing thereon, of a channel trackway at one end 110 of the frame, rollers loose in the trackway, a slide or carriage movable on the rollers, and a connection between the said slide or carriage for each louver for simultaneously swinging the louvers, said carriage comprising a plate having its side edges bent laterally to engage the frame wall, one edge resting upon the rollers, and a guide on the wall for engaging the other edge. 115

6. In a device of the character specified, the combination with a louver supporting frame and the louvers mounted to swing thereon, of a channel trackway at one end of the frame, rollers loose in the trackway, a 120 slide or carriage movable on the rollers, and a connection between the said slide or carriage for each louver for simultaneously swinging the louvers.

7. In a device of the character specified, a 125

130

louver supporting frame, louvers mounted to swing on parallel axes at the lower edge of the frame, a slide or carriage movable transversely of the louvers at one end of the frame, a guide on the frame for the slide or carriage, and a connection between the said slide or carriage and the louvers for operating said louvers, said connection comprising cranks at the ends of the louvers,
10 each crank having a portion journaled in the carriage.

8. In a device of the character specified, a

face plate or grill having an imperforate edge, and provided at the inner side of the said edge with inwardly and downwardly 15 extending oblique flanges having openings for receiving a securing means, said openings being in register with perforations of the grill.
